JOHN R. McGIFFERT, OF DULUTH, MINNESOTA, ASSIGNOR TO CLYDE IRON WORKS, OF DULUTH, MINNESOTA, A CORPORATION OF MAINE.

OPERATING MECHANISM FOR SCRAPER-BUCKETS.

1,231,275.

Specification of Letters Patent. Patented June 26, 1917.

Application filed January 17, 1914. Serial No. 812,642.

To all whom it may concern:

Be it known that I, JOHN R. McGIFFERT, a citizen of the United States, and a resident of Duluth, county of St. Louis, and State of Minnesota, have invented a new and useful Improvement in Operating Mechanism for Scraper-Buckets, of which the following is a specification, the principle of the invention being herein explained and the best mode in 10 which I have contemplated applying that principle, so as to distinguish it from other inventions.

The subject of the present invention is an operating mechanism for scraper buckets of 15 the type shown and described in Patent No. 987,352 issued March 21, 1911 to Geo. E. Field. The bucket in question is adapted for excavating and is intended to be operated by suitable cables, one of which passes 20 over a tower which is a necessary element of the invention described in the patent referred to. The bucket and the operating mechanism for the same, as shown in the patent referred to, are highly satisfactory 25 under certain conditions but it is desired to provide a mechanism which will not require the use of a tower, which it is often difficult to provide by reason of the conditions. The present invention, then, relates to mechanism 30 for operating this type of scraper buckets over a wide area and without any additional mechanism such as towers and the like. To the accomplishment of these and related ends said invention then consists of 35 the means hereinafter fully described and particularly pointed out in the claims.

The annexed drawing and the following description set forth in detail certain mechanism embodying the invention, such disclosed means constituting, however, but one 40 of various mechanical forms in which the principle of the invention may be used.

Figure 1 is a side elevation showing the scraper bucket and connections for the same; 45 and Fig. 2 is a similar elevation but showing more or less diagrammatically the various operating positions of the bucket.

In Fig. 1 there is shown a scraper bucket 1 which is open at its forward end 2 and has 50 attached to it at the other end 3 an upwardly extending brace 4 upon which are rotatably mounted two aligned and substantially vertically disposed sheaves 5 and 6. An operating cable 7 is attached at one end to a drum 55 8 and from this drum passes over the upper

sheave 5 and under the lower sheave 6. The cable then extends through suitably fixed sheaves or drums 9 and is secured at its other end to a second operating drum 10, disposed adjacent to the drum 8 and operated independently of the same. 60

The cable is permitted but limited movement through the sheaves, there being a stop in the form of a ring 11 attached to such cable adjacent to the open end 2 of the 65 bucket, this ring being of sufficient size to prevent its passage over the sheaves 5 and 6. In this way the movement of the cable over the sheaves in one direction is limited and such movement is limited in the other direction by a short second cable, preferably in 70 the form of a chain 12, which is attached to the lower part of the open end 2 of the bucket and then to such ring 11 attached to the main cable. The second cable or chain 75 may be attached at various heights at the open end of the bucket, as indicated by the apertures 13, thus causing various inclinations to be given such bucket when drawn in toward the operating sheaves. 80

When it is desired to draw out the bucket to the particular spot where it is designed to dig, the cable is wound in on the sheave 10, the other sheave 8 slackening away on the same, thus dragging the bucket 1 over the 85 ground without filling the same with earth. To operate the bucket the cable is pulled in the opposite direction by the sheave 8 and the inclination of the bucket may be varied by the resistance which is put upon the cable 90 by the other sheave 10. The pull on the bucket will come from two sources, first through the cable 7 and second through the chain 12, and it will depend, of course, upon the resistance which is placed upon the cable 95 as to what inclination the bucket will take. After the bucket has been filled the resistance on the cable 7 is diminished and the pull on the bucket is then entirely through the chain 12, thus drawing the same over the 100 ground on its bottom. When it is desired to dump the bucket the cable is pulled in both directions and the pressure on the two sheaves mounted on the bucket will then form a couple which will tend to upset the 105 bucket, as illustrated in Fig. 2. After being dumped the cable is drawn out, thus returning the bucket to the point of excavation.

A suitable brake may be applied to the sheave 10 for the purpose of varying the 110

resistance on the cable or the sheave may be controlled in other ways to secure this result. The movement of the bucket is, of course, at all times controlled by the influence of the couple operating through the two sheaves 5 and 6 which is produced by the pull on the cable 7 in either direction and the position of these sheaves relative to the direction of movement of the bucket, or 10 rather the direction in which the cable is led after passing over the sheaves.

The anchored sheaves 9 are shown in Fig. 2 as if one was above, but this is done for purposes of illustration only and it 15 will be understood that in practice these anchored sheaves will preferably be placed at the same elevation which will be substantially the same as that of the machine 15 bearing the operating sheaves 8 and 10. In 20 this way the use of a tower or in fact any structure as a part of the operating mechanism is eliminated, thus making the device simpler and giving it a greater field for use, as in certain cases it was not possible or 25 practical to construct the tower necessary in the former mechanism.

Other modes of applying the principle of my invention may be employed instead of the one explained, change being made as 30 regards the mechanism herein disclosed, provided the means stated by any of the following claims or the equivalent of such 35 stated means be employed.

I therefore particularly point out and 35 distinctly claim as my invention:—

1. The combination of a scraper bucket, a single continuous cable extending in the desired line of movement of said bucket in either direction therefrom, a member mounted on said bucket adjacent the rear thereof, two elements mounted on said member in line with the direction of movement of said bucket but in different horizontal planes in the normal position of said bucket, said 40 cable passing freely about said two elements at the rear of said bucket and being rendered capable of tilting said bucket in a vertical plane upon being tautened from 45

both ends simultaneously, and a single connection between said cable and the front 50 end of said bucket limiting relative movement of the two and permitting said cable to be used to haul in and out said bucket as well as tilt the same.

2. The combination of a scraper bucket, 55 a single continuous cable extending in the desired line of movement of said bucket in either direction therefrom, an upright member mounted at the rear of said bucket, two sheaves mounted on said member in line with 60 the direction of movement of said bucket but in different horizontal planes in the normal position of said bucket, said cable passing freely about said sheaves at the rear of said bucket and being rendered capable of tilting said bucket in a vertical plane upon being tautened from both ends simultaneously, and a single connection between said cable and the front end of said bucket limiting 65 relative movement of the two and permitting 70 said cable to be used to haul in and out said bucket as well as tilt the same.

3. The combination of a scraper bucket, a single continuous cable extending in the desired line of movement of said bucket in 75 either direction therefrom, an upright member mounted at the rear of said bucket, two sheaves mounted on said member in line with the direction of movement of said bucket but in different horizontal planes in the normal 80 position of said bucket, said cable passing over said upper sheave and under said lower sheave and being rendered capable of 85 tilting said bucket in a vertical plane upon being tautened from both ends simultaneously, and a single connection between said cable and the front end of said bucket limiting relative movement of the two and permitting 90 said cable to be used to haul in and out said bucket as well as tilt the same.

Signed by me this 6th day of January, 1914.

JOHN R. MCGIFFERT.
